(57) **CLAIM**

The ornamental design for a dryer, as shown and described.

DESCRIPTION

In a preferred embodiment, the nature of this product is an
air blowing device, such as a hand dryer.

FIG. 1 is a top, right front perspective view of a dryer of our
new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a top, left, front perspective view of a dryer
according to another embodiment of our new design in
which the dryer is a mirror image of the views shown in
FIGS. 1-5; and;

FIG. 9 is a top plan view thereof.

The broken line representations of the rear structure in FIG.
7, the edge contour in FIGS. 1-4 and 8 and the bottom
structure in FIG. 6 are for illustrative purposes only and
form no part of the claimed design.
